UNITED STATES PATENT OFFICE

EDWIN F. NELSON, OF CHICAGO, ILLINOIS, ASSIGNOR TO UNIVERSAL OIL PRODUCTS COMPANY, OF CHICAGO, ILLINOIS, A CORPORATION OF SOUTH DAKOTA

CONVERSION OF HYDROCARBONS

Application filed June 28, 1929. Serial No. 374,471.

This invention relates to an improvement in processes for the conversion of hydrocarbons into more valuable products.

More particularly, the invention relates to

- 5 an improvement in the handling of cracked distillates produced by the thermo decomposition of hydrocarbon oil whereby more suitable products are obtainable from the cracking process.
- 10 In the operation of commercial cracking processes, the resulting liquid distillate withdrawn from the receiver is charged with dissolved uncondensable gas and light hydrocarbons which are highly volatile. In operation, sufficiently converted vapors which do not condense below a certain point are removed from the usual dephlegmating or fractionating zones of the cracking process, and these vapors together with the uncondensable
- 15 20 gas formed in the process are condensed. This distillate and uncondensable gas collects in a receiver, the gas being removed from the top thereof and the liquid distillate from the bottom. It is this distillate which is found to be charged with dissolved uncondensable gas and highly volatile light hydrocarbons.

According to one of the methods used at present, the non-condensable gas removed from the receiver is passed through a gas separator. Thus, it is obvious that the use of a receiver with a gas separator permits the gas escaping from the receiver to carry with it considerable condensable fractions. In the chemical treatment, pumping operations and storage of distillates of this character, the dissolved non-condensable gas and very light distillate are lost by evaporation. With the escape of these constituents by evaporation a certain portion of the desirable relatively

- 25 30 35 40 45 heavier constituents of the distillate are carried away as well, so that the resultant loss is not only of the undesirable "wild" constituents, but also of certain desirable light ends of gasoline which by the employment of my invention may be saved.

It is a primary object, therefore, of the present invention to stabilize both the non-condensable gas and condensed distillate so that the non-condensable gas may be stripped

tions and thus be substantially dry, while the distillate will be stripped of substantially all of the non-condensable gas and very light ends.

As a feature of the present invention, the 55 stabilization of the gas and the distillate may take place under plant pressure, that is, the pressure within the stabilizer may be the same as the pressure on the cracking process which produced the distillate and non-condensable 60 gas, or it may be reduced relative thereto.

In one specific embodiment of my invention, I employ a tower or other suitable means as a stabilizer element to stabilize the non-condensable fractions from the pressure distillate. The latter may be then chemically treated, transferred and stored with minimum loss of the desirable components thereof.

Other advantages and objects of the invention will be more apparent from the following description.

By reference to the single figure in the drawing, which is a diagrammatic side elevational view of apparatus in which the 75 process may be carried out, the operation will be obvious to those skilled in the art.

Referring more in detail to the drawing, raw oil may be supplied through line 1 by means of pump 2 and a dephlegmator 3, 80 where it is preheated by partially condensing the vapors entering the bottom thereof, as will be hereinafter described. A hot oil pump 4 taking suction from the bottom of dephlegmator 3 through line 5 delivers the 85 preheated oil and reflux condensate to a heating coil 6 located in furnace 7 and heated by means of burner 8. This furnace may be of any design suitable for heating the oil in coil 6 to the desired temperature. The 90 heated oil passes out through transfer line 10, in which is interposed valve 11, to expansion chamber 12. Vapors separating from non-vaporous products in chamber 12 may pass out through vapor outlet line 14, 95 controlled by valve 13, discharging in the bottom of dephlegmator 3 where partial condensation occurs, the vapors remaining uncondensed after passage through the dephlegmator passing out through vapor outlet 100

line 15, controlled by valve 16, into condenser coil 17. Unvaporized residue may be withdrawn from the chamber 12 through line 9, controlled by valve 9'.

5 The distillate and uncondensable gas pass out through line 18 through stabilizer 19, which may be of any suitable construction, whereby intimate contact of vapor and liquid may be obtained in order to arrive 10 at equilibrium conditions. If stabilizer 19 requires heating, means such as a steam coil in the bottom thereof, as indicated at 20, may be provided.

One of the novel features of the present 15 invention takes advantage of the fact that the uncondensable gas escaping through line 21 will, through reduction in pressure by means of valve 22, become greatly cooled, depending upon the differential pressure employed between the stabilizer 19 and the 20 pressure prevailing in coil 23. If necessary, an additional cooling element may be employed, such as a coil 24 located at or near the top of stabilizer 19. If all of the 25 expanded gas is not necessary to obtain the requisite cooling, then regulated portions thereof may be passed through coil 23 and the remainder diverted from the coil by means of by-pass line 35, controlled by valve 36.

A direct gradient will necessarily prevail 30 between the point at which line 18 enters the stabilizer and the top of the tower. Likewise, a direct gradient will prevail from the 35 heating means at the bottom of the tower to the point at which line 18 enters the stabilizer; or, in other words, a gradient will prevail more or less uniformly from the bottom of the stabilizer to the top.

40 The uncondensable gas passing through coil 23 will, at reduced pressure, pass out through line 25. The stabilized condensate from the bottom of stabilizer 19 may pass out through line 26 and cooler 27 into receiving 45 drum 28 from which the condensate may be withdrawn through valve 29. By controlling the temperature conditions at the top of dephlegmator 3 a portion of the condensate may be withdrawn from receiver 28 and forced through line 30 and valve 31 by pump 32. Provision is made through valve 33 for releasing gas from receiver 28, which gas, under normal conditions, will not be liberated at the top of stabilizer 19 through line 21, pressure on the system being controlled by valve 22; that is, valves 11, 13 and 16 will be open.

In an alternate method of operation, by the employment of the valves just mentioned, differential pressures may be employed between the heating, expansion, dephlegmating and stabilizing zones, although this operation will not be the preferable one, since material pressure reduction through valve 22 in line 21 is desired to get

a proper cooling effect for the top of stabilizer 19. Since gas relief valve 33 on receiving drum 28 will not normally be in use, the liquid level in stabilizer 19 should be ascertained by means of a gauge glass 34 located 70 on the bottom thereof.

It will be understood that, by means of the present invention, a practically complete stabilized distillate may be recovered from the bottom of stabilizer 19; with the fixed gas 75 discharging from the top of the stabilizer containing practically no gasoline-like material. By the control of pressure reduction by means of valve 22, and by means of the cooling means 24 and heating means 20, the character of both the stabilized condensate and the uncondensable gas leaving stabilizer 19 may be varied within relatively wide limits.

As an example of the conditions prevailing in one operation employed in my invention, a 24° Bé. gravity Mid-continent reduced crude oil may be charged to the cracking unit. The temperature of the discharge of heating coil 6 may be approximately 910° F.; the temperature at the top of dephlegmator 3 may be 80 approximately 525° F.; the temperature of the condensate and non-condensable gas entering stabilizer 19 through line 18 may be approximately 95° F.; the temperature of the gas exiting from the top of stabilizer 19 may 85 be about 75° F. Steam may be employed at the bottom of stabilizer 19 in coil 20 so that the temperature of the stabilized condensate leaving through line 26 may be about 165° F. and by passage through cooler 27 may be reduced to approximately 85° F. 100

Pressures prevailing in the system may be approximately 275 pounds to the square inch at the discharge of pump 4, while the stabilizer may be maintained under a pressure of 105 approximately 190 pounds, the difference between these two pressures being due to hydrostatic head and friction drop. The pressure may be reduced by valve 22 to substantially atmospheric, or just enough above atmospheric to overcome friction in passing through the remainder of the apparatus. This pressure reduction will bring about a corresponding temperature reduction of 50° F., which under these specific conditions, will 110 be sufficient to condense substantially all of the portions ascending in tower 19 when brought into contact with the cooling coil. 115

A yield of about 65% pressure distillate 120 will be obtained having an initial boiling point of approximately 110° F. and an end point of about 550° F., containing about 73% of 437° F. end point gasoline. The uncondensable gas in stabilizer 19 discharged from line 25 will contain, by the charcoal test, less than a gallon of condensable gasoline per thousand cubic feet. In operation without the stabilizer, under the same conditions, the fixed gas from the receiving drum 28 will 125 show a gasoline content of approximately two 130

gallons per thousand cubic feet. A material loss will also occur by reason of the fact that the distillate will have an initial boiling point of about 90° F. and will show a vapor loss in handling and treating of approximately 2%.

It is to be understood that the specific figures given in this illustrative run are not to be taken in any sense as a limitation of the invention. The figures are merely illustrative of one specific embodiment of the invention. The invention in its broad concept contemplates, first the separation of the uncondensable gas from the liquid distillate under superatmospheric pressure, the subsequent reduction in pressure on said uncondensable gas thus bringing about a corresponding decrease in temperature, which decrease in temperature is utilized as a cooling medium to strip condensable fractions from the gas during the separating step.

I claim as my invention:

1. In a process of hydrocarbon oil conversion wherein said oil is heated to cracking temperature and sufficiently converted vapors and non-condensable gas separated from insufficiently converted vapors and residue, superatmospheric pressure is maintained on said oil and vapors, and said sufficiently converted vapors and non-condensable gas are condensed and cooled, the improvement which comprises separating the uncondensable gas from the condensed distillate under superatmospheric pressure in a separating zone, removing said separated gas from the separating zone, reducing the pressure thereon to thereby reduce its temperature, and returning regulated portions of said gas under reduced pressure to said separating zone and passing same therethrough in indirect contact with the gas being separated therein to condense condensable portions associated with said gas.

2. In hydrocarbon oil pressure cracking processes wherein the cracked vapors and gases are cooled under superatmospheric pressure to condense the vapors, the improvement which comprises introducing the condensed distillate and gas to a stabilizing zone maintained under the superatmospheric pressure of the cracking process, separating the gas from the distillate in said zone, removing the separated gas under pressure from the stabilizing zone and reducing the pressure thereon, and passing the expanded gas in indirect heat exchange relation with the gas being separated in said zone.

In testimony whereof I affix my signature.
EDWIN F. NELSON.
